CLAIM

The ornamental design for a bottle cap, as shown and described.

DESCRIPTION

FIG. 1 is a perspective view of a first embodiment of a bottle cap, shown in a position of use on a bottle drawn in broken lines.

FIG. 2 is a top view of the bottle cap of FIG. 1, shown removed from the bottle.

FIG. 3 is a side view thereof.

FIG. 4 is a front view thereof.

FIG. 5 is a perspective view of a second embodiment of a bottle cap, shown in a position of use on a bottle drawn in broken lines.

FIG. 6 is a top view of the bottle cap of FIG. 5, shown removed from the bottle.

FIG. 7 a side view thereof; and,

FIG. 8 is a front view thereof.

The broken lines depict environment and form no part of the claimed design.

1 Claim, 2 Drawing Sheets
